UNITED STATES PATENT OFFICE.

ALBERT L. COLE, OF AUBURNDALE, MASSACHUSETTS, ASSIGNOR TO RUSSELL C. BERRY, OF MARLBORO, MASSACHUSETTS.

JAR OPENER.

Application filed August 9, 1920. Serial No. 402,150.

To all whom it may concern:

Be it known that I, ALBERT L. COLE, a citizen of the United States, residing at Auburndale, in the county of Middlesex and State 5 of Massachusetts, have invented a new and useful Improvement in Jar Openers, of which the following is a specification, reference being had therein to the accompanying drawings.

10 My invention relates to a jar opener for removing the covers from preserving jars and similar containers.

In removing the cover from a preserving jar in order to remove the contents, it is customary to insert the sharp edge or point of some suitable instrument between the cover and the gasket on the mouth of the jar and then force the cover upwardly in order to permit air to be admitted to the jar to 15 destroy the partial vacuum therein. This operation is generally more or less difficult, especially if the jar has remained for a long period of time and considerable force is required. At the same time, the circular form 20 of the jar tends to make the operation increasingly difficult and awkward, because the gasket hardens with age and resists the penetration of the instrument and the latter slips from the curved surface of the jar.

25 The main object of my invention is the provision of a simple and efficient one-piece instrument of low cost whereby jar covers may be removed easily and expeditiously without requiring the exercise of undue force.

30 Another object of the invention is the provision of a jar opener adapted for use on jars having wire clamps and being so formed that the clamps on the jar may be utilized as 35 a fulcrum and for holding the opener against slipping or displacement during the opening operation.

Other objects of the invention will be more specifically set forth hereinafter.

40 My invention contemplates a jar opener in the form of a lever having its operating end sharpened and adapted for insertion between the cover of the jar and the gasket; said lever being provided with means for holding 45 one of the wire clamps of a jar in order that the clamp may be used as a fulcrum in operating the lever.

In the drawings illustrating the preferred form of my invention, Figure 1 is a view in

perspective of the upper half of a jar provided with wire clamps showing a jar opener made in accordance with my invention being applied thereto for removing the cover; Fig. 2 is a side elevation of the jar opener and Fig. 3 is a plan view of the same looking downwardly, in Fig. 2.

Referring to the drawings illustrating the preferred embodiment of my invention, 5 designates a lever in the form of a flat bar, having its operating end 6 beveled to form a sharp edge. Near the end 6 is formed an off-set open loop 7 which is designed to receive one of the wire clamps on the jar to hold it while it is being used as a fulcrum in the operation of the opener. The handle end 8 of the lever 5 may be provided with a hole 9 whereby the opener may be hung on a hook or nail when not in use.

In Figure 1 illustrating the method of using my opener, 12 designates the jar, having a cover 13 and gasket 14 arranged between the cover and the flange 15 of the mouth of the jar. This type of jar is provided with wire clamps comprising a cover clamp 16 which is adapted to go over the top of the cover 13 and rest between two lugs 18 after the jar has been filled and the cover placed in position. A second clamp 20, which may be termed the locking clamp, has its ends mounted in small plates 22 carried on a wire 23 fastened around the neck of the jar. Near each end the locking clamp has a loop 25 formed by turning the wire and each loop is adapted to receive and hold one end of the cover clamp 16 so that the cover clamp is carried by the locking clamp. After the cover clamp 16 has been placed over the top of the jar on the cover the locking clamp 20 is then pressed downwardly against the body of the jar thereby drawing the cover clamp down 95 tightly on the cover and locking it in place. All of the foregoing is of old and well known construction and constitutes no part of my invention.

In the use of my opener the locking clamp 100 is pushed upwardly thereby releasing the cover clamp which is then turned downwardly over the cover toward the side of the jar. The opener is then arranged with the loop 7 pointing downwardly, with the cover 105 clamp 16 lying within the loop 7 and the end 6 of the opener is placed above the locking clamp 20. At the same time that the

- opener is arranged in this position the sharpened edge of the end 6 is brought to bear between the cover 13 and the gasket 14. A slight upward pressure on the handle end 5 of the opener has the effect, owing to the construction of the clamp, of throwing the sharpened edge forward in between the cover and the gasket, thereby raising the cover sufficiently to admit air into the jar.
- 10 In this operation it will be noticed that as the handle end of the lever is moved upwardly it tends to raise the cover clamp, thereby forcing the sharpened edge 6 of the opener in between the cover and the gasket.
- 15 I have found from experience that this form of jar opener requires very little force because of the leverage and that it will open the most obstinate jar with ease and facility.

While my opener is designed primarily 20 for use in connection with jars having clamps, as shown in Fig. 1 of the drawings, yet it may be used to open ordinary jars, and when so used, the loop 7 constitutes an abutment against which the thumb may be placed 25 in pressing the operating end of the opener in between the cover and the gasket and thereby my opener is susceptible of a more efficient use in such cases.

It is to be understood that my invention is 30 not to be limited to the precise form of lever shown and illustrated in the drawings because it is susceptible of embodiment in various other forms since the essential features of the lever comprise merely a sharpened point or edge and means for receiving and holding a wire clamp as a fulcrum during the operation of the lever. The form shown, however, is preferable because of its 35 cheapness since it may be stamped out of a suitable sheet metal by dies formed for that purpose.

What I claim is:—

1. A jar opener comprising a lever having one end adapted to be inserted under the 45 cover of the jar and provided with an offset open loop adapted to receive and hold the cover clamp of said jar so that the same may

be used as a fulcrum during the opening operation.

2. A jar opener comprising a flat lever 50 having one end sharpened for insertion under the cover of the jar and provided with means for holding one of the wire clamps of said jar and using it as a fulcrum during the opening operation; said holding means 55 being so formed that the said clamp is held securely against movement longitudinally the said lever while it is being operated.

3. A jar opener comprising a lever having a sharpened edge adapted to be inserted 60 between the cover and gasket of a jar for opening the same, and being provided with means for receiving and holding one of the wire clamps of said jar in order that the same may serve as a fulcrum during the 65 opening operation.

4. A jar opener comprising a lever having a sharpened edge adapted to be inserted between the cover and gasket of a jar for opening the same, and being provided with 70 a recess for receiving and holding one of the wire clamps of said jar in order that the same may serve as a fulcrum during the opening operation.

5. A jar opener comprising a lever having 75 a sharpened edge adapted to be inserted under the cover to be removed and being provided with an open loop adjacent the sharpened end; said loop being adapted to receive and hold the cover clamp of the jar which 80 serves as a fulcrum when the said lever is held in engagement with the locking clamp of said jar.

6. A jar opener adapted to be stamped from flat metal, and being in the form of a 85 flat lever having its edge at one end sharpened, and the other end being suitable for use as a handle, said lever being provided with an offset open loop adjacent the sharpened edge, said loop being substantially perpendicular 90 to the flat sides of said lever.

In witness whereof, I hereunto set my hand this fifth day of August, 1920.

ALBERT L. COLE.
